UNITED STATES PATENT OFFICE

WALTHER PRIELIPP, OF DORTMUND, GERMANY

SHEET PILING

Application filed August 28, 1930, Serial No. 478,479, and in Germany August 28, 1929.

This invention relates to sheet piling wall constructions and more especially to those of Z or double-bent section form, its chief object being to provide a method and means 5 of increasing the moment of resistance of the same.

It is well known that difficulties in rolling make it impracticable to form Z or double-bent sections of any great length and/or 10 cross-sectional width and that the formation thereof is limited by the diameter of the rolls generally used in the rolling mills. However, since Z sections of sheet piling having a high moment of resistance are often required, other ways and means must be found 15 to meet requirements and conditions. The present object is so to do by providing a method and means of increasing the moment of resistance of such piling, and according 20 thereto given pairs of piling members have each combined therewith at least one reinforcing member.

The invention will be best understood by further description with reference to the attached drawing illustrating several practicable embodiments by way of example and wherein:

Fig. 1 is a cross-sectional or top plan view of two assembled Z-shaped sections forming 30 part of a wall and showing the combination therewith of a reinforcing member according to the invention;

Fig. 2 is a similar view of a somewhat different arrangement;

Fig. 3 is another showing a combination of 35 the ideas of the preceding two figures;

Fig. 4 is a further similar view illustrating a modification based upon the idea of Fig. 2; and

Fig. 5 represents a longitudinal section 40 through a piling wall according to the invention, making further exemplification of the application of the invention.

It may facilitate understanding at the outset to explain that in the ramming of one section after another, there is tendency to 45 rotate around a central longitudinal axis and this tendency leads to an irregular formation of the wall with resultant decrease in resistive power. There is also tendency of the

sections pulling apart or breaking the connection between each other during the ramming and this leads to considerable difficulty as also delay in properly constructing the wall. It is the purpose of this invention to 55 provide a method and means of eliminating these two great objections, the same being done in a very simple but most efficient way.

In the embodiment illustrated in Fig. 1, two sheet piling sections of Z-shape form are 60 shown with their side flanges or longitudinal edges *a* and *b* connected in a joint *c* by interlocking of claw and bulbous portions fitting together. Combined with these is shown an I section *d* applied at the outer side thereof 65 so as to press against their joint or line of union for substantially the full length thereof. This backing or reinforcing member prevents relative rotation of the sections and adds rigidity with greatly increased resistive 70 motion to the wall.

In Fig. 2, a different form of reinforcing member embodying a flat plate *g* is shown similarly applied to the side flanges *e* and *f* of corresponding sections, the opposite 75 flanges *h* and *i* of which have similar but only half-sized reinforcing members *k* and *l* applied thereto. A combination of these two ideas is shown in Fig. 3, wherein I sections *d* (like those shown in Fig. 1) are combined 80 with the side flanges *a*, *b* and *m* of interconnected sections, these members being welded or otherwise secured to the section ends or not as desired.

Fig. 4 shows a modification in which a 85 plate *t* is applied to the side flanges of assembled pairs of sections as in Fig. 2, while pairs of ball and socket plates *n* and *o* are received at their opposite flanges, the latter being for the purpose of insuring better guidance and 90 stability in ramming into place.

Fig. 5 illustrates a longitudinal section 95 through a sheet piling wall backed up by filling material *p* at one side and by water at the other. This wall is held back as by an anchor brace indicated at *q*. In a case of this kind, the reinforcing members or plate irons (being flat in this example) which increase the moment of resistance need be provided only in the region and at the level in- 100

dicated at r in this figure, but are not then driven into the ground or bottoms as ordinarily and as really preferred. The sheet piling wall itself is represented at s .

5 It will be understood that the reinforcing members may comprise plates or sections of various kinds and forms.

The above described method and means of construction provides a trough-shaped 10 sectional wall of considerably higher moment of resistance than is otherwise obtainable with Z sections. Carrying the idea a step further, it is possible to combine the parts in substantially unitary and more rigid structures by welding or otherwise connecting together along the flanges forming the locking joints and reinforcement braces. Such a 15 welding is represented by the spots denoted by w between the overlapping portions of sections and reinforcement members. In each 20 figure, the reinforcing member braced against a connected pair of sections at one side is shown joined unitarily therewith by welding at and between its longitudinal edges, being 25 thus made rammable therewith as if the three parts were merely one. The half-sized members (k and l) at the other side of the wall may likewise and similarly be welded to 30 the opposite flanges of the sections to permit 35 ramming therewith as unitary parts. In the modification of Fig. 3 however, where the reinforcing member at said opposite side is of full size and bears against the joint with another section, the welding is shown effected 40 only along one-half of its bracing surface so as to permit ramming as a part of each unit and yet enable other sections to be connected and rammed therewith.

This welding together has the advantage 45 of making the axis of gravity coincide more or less exactly with the neutral axis of the piling. As an alternative, only one side flange of a section in each case need be combined with a reinforcement members such as 50 described. In the case of such arrangement the axes of the individual sections will be displaced to some extent, but this displacement would not be objectionable or give rise to any difficulty, inasmuch as the axis of the wall itself would not be displaced.

Of course, it is unnecessary to increase the 55 moment of resistance of all the assembled pairs of Z -sections. The reinforcement may be restricted to the points or areas where heavier loads or stresses occur. On the other hand, it is not always essential that the attached reinforcing members should extend the entire length of the piling members. In 60 some instances it may be sufficient to apply the increased resistance only to certain points or areas where the greatest moments or stresses occur as represented in Fig. 5, so that the piling members will become in effect "beams" of uniform resistance to flexation.

65 It must be emphasized as an extremely

great advantage, that the invention enables a theoretically perfect basis to be established for calculating the moment of resistance, and especially in the parts most subjected to stress, where an uncertain basis of calculation 70 leads in most cases to a waste of material. The invention accordingly enables, for the first time, a satisfactory basis to be established for the economic employment of Z -section sheet piling members and especially 75 in the case of walls in which local loads or impacts (such as the bumping of vessels) are to be expected. These loads may be of temporary or permanent character.

Having thus described my invention, what 80 I claim as new and desire to secure by Letters Patent of the United States is:—

1. The method of increasing the moment of resistance of sheet piling walls formed by Z -shaped sections interconnected in pairs, 85 which consists in applying a reinforcing backing member against the side flanges or longitudinal edges of each pair at and along the point of connection with each other on opposite sides of the wall's neutral axis so as 90 to prevent relative rotation of the members and tendency thereof to pull apart during ramming into place.

2. The method of increasing the moment of resistance of sheet piling walls formed by 95 Z -shaped sections interconnected in pairs, which consists in applying a backing and reinforcing plate-member against the longitudinal edges of each pair along their line of union, or connection on opposite sides of the 100 wall's neutral axis and welding said backing and reinforcing members to the section ends.

3. A sheet piling wall comprising a series of Z -shaped sections interconnected longitudinal edge-to-edge and reinforcing backing members applied against said edges there-of along the lines of jointure so as to prevent relative rotation in ramming. 105

4. A sheet piling wall according to claim 3, wherein the reinforcing and backing members comprise I-shaped sections which may be secured to the section edges for greater strengthening. 110

5. A sheet piling wall comprising a series of Z -shaped sections interconnected longitudinal edge-to-edge and reinforcing backing members applied against edges of each connected pair on opposite sides of the wall's neutral axis to bear against them with a strengthening force and effect offsetting displacement or disconnection tendencies during 115 ramming. 120

6. A sheet piling wall according to claim 5, wherein the reinforcing members on one side of the neutral axis are formed by interconnected flat plate-members joined and rammed together therewith. 125

7. A sheet piling wall according to claim 5, wherein the reinforcing members on one side of the neutral axis comprise I-shaped 130

beam sections and those on the other side comprise interconnected flat plate sections joined and rammed together therewith to insure proper guidance.

5 8. A sheet piling wall according to claim 5, wherein the reinforcing members at either side of the neutral axis are welded to the section edges against which they bear.

10 9. A sheet piling wall comprising a series of Z-shaped sections connected longitudinal edge-to-edge having combined backing and reinforcing members applied to bear against said edges thereof on opposite sides of the wall's neutral axis; those on one side of said 15 axis comprising unitary plate-members and those on the other side comprising interconnected plate-members and the same being of a length to produce an effect similar to that of a girder of uniform resistance to flexa-
10 tion.

25 10. A sheet piling wall comprising a series of Z-shaped sections connected longitudinal edge-to-edge having combined backing and reinforcing members bearing against said edges along the lines of interconnection on opposite sides of the wall's neutral axis; those at one side comprising flat plate-members and those at the other side comprising interconnected plate-members which may be 30 welded to the section edges for greater securing and strengthening if desired.

In testimony whereof I affix my signature.
